(57) **CLAIM**

I claim, the ornamental design for a trunk, as shown and described.

DESCRIPTION

FIG. 1 is a front perspective view, taken from above, of a trunk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof, taken from below;

FIG. 9 is a front perspective view, taken from above, of the trunk in another embodiment;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a rear perspective view thereof, taken from below;

FIG. 17 is a front perspective view, taken from above, of the trunk in another embodiment;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof;

FIG. 24 is a rear perspective view thereof, taken from below;

FIG. 25 is a front perspective view, taken from above, of the trunk in another embodiment;

FIG. 26 is a front view thereof;

FIG. 27 is a rear view thereof;

FIG. 28 is a left side view thereof;

FIG. 29 is a right side view thereof;

FIG. 30 is a top view thereof;

FIG. 31 is a bottom view thereof;

FIG. 32 is a rear perspective view thereof, taken from below;

(Continued)

FIG. 33 is a front perspective view, taken from above, of the trunk in another embodiment;
FIG. 34 is a front view thereof;
FIG. 35 is a rear view thereof;
FIG. 36 is a left side view thereof;
FIG. 37 is a right side view thereof;
FIG. 38 is a top view thereof;
FIG. 39 is a bottom view thereof; and,
FIG. 40 is a rear perspective view thereof, taken from below. The broken lines illustrate portions of the trunk and form no part of the claimed design.
